UNITED STATES PATENT OFFICE.

HERBERT ABRAHAM, OF NEW YORK, N. Y., ASSIGNOR TO THE RUBEROID COMPANY,
A CORPORATION OF NEW JERSEY.

SHINGLE STRIP.

Application filed August 5, 1921. Serial No. 489,971.

To all whom it may concern:

Be it known that I, HERBERT ABRAHAM, a citizen of the United States, residing at the city, county, and State of New York, have 5 invented certain new and useful Improvements in Shingle Strips, of which the following is a specification.

This invention relates to improvements in prepared roofing shingle strips having alternating projections and indentations along their lower edges, which strips when laid in overlapping courses form a roofing having the appearance of a plurality of individual shingles.

15 The objects of the invention are to provide strips of this character which are constructed to be laid in interlocked relation with the butts of each strip held down in such manner as to prevent their being accidentally pulled or slipped out of place but to permit of expansion or contraction without buckling. My improved strips may be laid either with the butts flat, or bent in hook-form as described in my copending application Serial No. 473,136, filed May 27, 25 1921.

I attain these objects, as well as others not specifically stated, by means of the novel features of construction hereinafter described 30 and illustrated in the accompanying drawings, which show a preferred form and in which:

Figure 1, is a plan view of one of my improved strips;

35 Fig. 2 is a plan view of a section of a roofing composed of my improved strips.

Fig. 3 is a section of a roofing laid with strips having their butts bent in hook-form;

40 Fig. 4 is a rear plan view of one of the strips showing the butts bent in hook-form;

Fig. 5 is a section on the line 5—5 of Fig. 5; and

45 Fig. 6 is a plan view of a sheet of roofing material with the lines of cutting for forming the strips indicated thereon.

The strips each comprise a body portion 1 having parallel straight edges, the upper edge 2 being intact, and the lower edge being broken, at equidistant points, by indentations or recesses 3 to leave integral projecting portions, which are similar in size and shape to the indentations but reversed in position. The projections each comprise two mutually similar symmetrical portions 4—5, preferably of trapezoidal shape, as

shown, disposed one above the other, and with the narrow end of the upper portion 4 joined to the wide end of the lower portion 5.

The strips may be of any desired length 60 so as to include any desired number of projections. As shown in the drawings each strip is formed with two projections. The strips are intended to be laid end to end in a row to form a course and to have similar 65 courses superposed successively thereon in overlapping relation.

The strips may be laid either with the lower portions 5 of the projections in flat condition, as shown in Fig. 2, or with such 70 portions bent under in hook-form, as shown in Fig. 3.

When the strips are laid flat, the laterally extending spurs of the portions 5 of each projection will engage under the portions 4 75 of the adjacent projections of the next underlying strip, and will thus interlock the strips of the several courses.

The strips may also be used with the portions 5 of each projection bent back in hook-form and inserted under the tops of the recesses 3 of the immediately underlying strip, so that the portions 5 are covered by the body portion 1 of the underlying strip, and that the laterally extending spurs of the 85 portions 5 project at each side of the tops of the recesses 3 thereof. This provides a roof covering in which the butts of the exposed portions 4 are hooked tightly down. The fact that the distance, measured horizontally, across the tips of the spurs of the 90 portions 5 is greater than the width of the top of the recesses 3, respectively, prevents the butts from being accidentally blown or pulled out of place.

95 As shown in Fig. 6, strips of the character described may be formed without waste, by cutting lengthwise a web or sheet of roofing material sufficiently wide to accommodate two strips widthwise, in such manner as to leave projecting portions 4—5 alternating at either side of the cut, and cutting crosswise, at staggered points, to divide the strips into elements of desired length having their ends so shaped that when laid end to end, the contiguous end portions form a recess similar to the recesses 3 between the adjacent projections 4—5. Preferably, to facilitate laying, the units consist of strips each 100 having two or more projections but if de- 105 110

sired the units may consist of elements each having a single projection.

What I claim is:

1. A prepared roofing strip having its lower edge formed with alternating projections and recesses, each projection consisting of two mutually similar symmetrical portions, the projections and recesses being substantially similar in size and shape but reversed in position, the ends of the strip being so shaped that when two of said strips are laid end to end, the contiguous ends form a recess which is similar to the first-mentioned recesses.
2. A prepared roofing strip having its lower edge formed with alternating projections and recesses, each projection consisting of two mutually similar trapezoidal-shaped portions disposed one above the other, the projections and recesses being substantially similar in size and shape but reversed in position, the ends of the strips being so shaped that when two of said strips are laid end to end, the contiguous ends form a recess which is similar to the first-mentioned recesses.
3. A prepared roofing strip having its lower edge formed with alternating projections and recesses which are substantially similar in shape and size but reversed in position, each projection consisting of two mutually similar trapezoidal-shaped portions disposed one above the other with the narrow end of the upper portion joining the wide end of the lower portion, the ends of the strip being so shaped that when two of said strips are laid end to end, the con-

tiguous ends form a recess which is similar to the first-mentioned recesses.

4. A prepared roofing element having a projection on its lower edge consisting of two mutually similar symmetrical portions, the ends of the element being so shaped that when two of said elements are laid end to end, the contiguous ends form a recess which is similar in size and shape to the projection but reversed in position.

5. A prepared roofing element having a projection on its lower edge consisting of two mutually similar trapezoidal-shaped portions disposed one above the other with the narrow end of the upper portion joining the wide end of the lower portion, the ends of the elements being so shaped that when two of said elements are laid end to end, the contiguous ends form a recess which is similar in size and shape to the projection but reversed in position.

6. A roof covering comprising a plurality of prepared roofing units laid end to end in overlapping courses, with their lower edges forming alternating projections and recesses which are mutually similar in size and shape but reversed in position, each projection consisting of two similar trapezoidal-shaped portions disposed one above the other with the narrow end of the upper portion joining the wide end of the lower portion; and with the tips of the wide end of the lower portion of each projection underlying the upper portion of the adjacent projections of the next lower course.

HERBERT ABRAHAM.
